UNITED STATES PATENT OFFICE

CHRISTOPHER H. G. HART, OF LOS ANGELES, CALIFORNIA.

TOY VEHICLE

Application filed March 11, 1929. Serial No. 346,053.

The present invention relates to a toy vehicle and the prime object thereof is to provide a structure of this nature which is adapted to travel along the ground with a motion 5 simulating the motion of a horse or other animal.

Another very important object of the invention resides in the provision of a vehicle with a body simulating that of an animal such as a horse or the like, together with the driving means whereby the rider of the vehicle may propel the same along the ground and in addition thereto, the body of the vehicle is mounted upon a steel spring bar so 10 that the body is adapted to swing upwardly and downward as it travels, thereby to provide not only a straight forward motion to the vehicle but also to simultaneously permit an upward and downward rocking or swinging 15 of the body and operate it during the travel.

Another very important object of the invention resides in the provision of an improvement over the patented structure shown 20 in Letters Patent No. 1,598,966 granted to me on September 7, 1926, by providing a structure which is exceedingly simple, inexpensive to manufacture, strong and durable, compact and convenient in its arrangement of parts 25 and otherwise well adapted to the purpose for which it is designed.

With the above and numerous other objects in view as will appear as the description proceeds, the invention resides in certain novel 30 features of construction, and in the combination and arrangement of parts as will be hereinafter more fully described and claimed.

In the drawings:

Figure 1 is a side elevation of the vehicle 35 embodying the features of my invention,

Figure 2 is a top plan view thereof,

Figure 3 is a rear elevation thereof,

Figure 4 is an enlarged detail section taken 40 substantially on the line 4—4 of Figure 2, and

Figure 5 is a detail section taken substantially on the line 5—5 of Figure 4.

Referring to the drawing in detail it will be 45 seen that the numeral 5 denotes a body shaped to simulate that of a running animal, such as

a horse and being provided with a seat or saddle 6.

A steering post 7 extends substantially vertical through the forward portion of the body and is rockably mounted therein. The 55 lower end of this post 7 has a fork 8 thereon between the extremities of which is journaled a disk wheel 9 operable by foot pedals 10. Handle bars 11 are provided at the upper end of the post.

A steel spring bar 12 has a curved end secured as at 14 to the under edge of the rear portion of the body 5 and curved downwardly to incline downwardly and rearwardly and terminate in a clamp loop 15 in which is 60 mounted a bushing 16 for receiving rear axle 17.

Disk wheels 18 are journaled on the ends of the axle and are preferably smaller in diameter than the front or drive wheel 9. Brace 70 bars 19 have sleeves 20 secured about the end portions of the axle and these braces incline upwardly and inwardly and are secured to an intermediate portion of the spring 12.

One of the braces is offset intermediate its 75 ends so as to form a step 21 to enable one to more easily mount the vehicle, as will be quite apparent. The toy vehicle thus described may be driven along the ground by an operator on the seat or saddle 6 for propelling the vehicle by rotation of the pedals 10.

The body 2 supporting the rider may, during this travel, be rocked or swung up and down with respect to the axis of the front 85 wheel 9 with a result that an action closely resembling that of a running or galloping animal is produced.

It is thought that the construction, utility, and advantages of this invention will now be 90 quite apparent to those skilled in this art without a more detail description thereof.

The present embodiment of the invention has been disclosed in considerable detail merely for the purposes of exemplification 95 since in actual practice it attains the features of advantage enumerated as desirable in the statement of the invention and the above description.

It will be apparent that changes in the de- 100

tails of construction, and in the combination and arrangement of parts may be resorted to without departing from the spirit or scope of the invention as hereinafter claimed or sacrificing any of its advantages.

Having thus described my invention, what I claim as new is:

1. In a toy vehicle of the class described, a body simulating the appearance of a running animal, a post rockable through the forward portion of the body and having its lower end provided with a fork, a wheel journaled in the fork, pedals on the wheel for rotating the same, a handle bar at the upper end of the post, a spring secured to the under portion of the rear of the body and curved downwardly and inclining downwardly and rearwardly, an axle on the rear end of the spring, wheels journaled on the ends of the axle, braces extending diagonally between the axle and the spring.

2. In a toy vehicle of the class described, a body simulating the appearance of a running animal, a post rockable through the forward portion of the body and having its lower end provided with a fork, a wheel journaled in the fork, pedals on the wheel for rotating the same, a handle bar at the upper end of the post, a spring secured to the under portion of the rear of the body and curved downwardly and inclining downwardly and rearwardly, an axle on the rear end of the spring, wheels journaled on the ends of the axle, braces extending diagonally between the axle and the spring, one of said braces having an offset intermediate portion to form a step.

In testimony whereof I affix my signature.

CHRISTOPHER H. G. HART.
